Primary Examiner — Jennifer L Rempfer*Assistant Examiner* — Edward P Jones(74) *Attorney, Agent, or Firm* — NSIP Law(57) **CLAIM**

I claim the ornamental design for a fixture for dental implant, as shown and described.

DESCRIPTION

FIG. 1 is a front perspective view of a fixture for dental implant showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a bottom perspective view thereof;

FIG. 9 is a cross-sectional view taken through line 9-9 in FIG. 4; and,

FIG. 10 is a cross-sectional view taken through line 10-10 in FIG. 5.

The broken lines in the figures depict portions of the fixture for dental implant which form no part of the claimed design.
